UNITED STATES PATENT OFFICE.

LAZAR EDELEANU, KARL PFEIFFER, KARL GRESS, AND PAUL JODECK, OF BERLIN,
GERMANY.METHOD OF REFINING HEAVY MINERAL OILS BY MEANS OF SULPHUR DIOXIDE IN
A CONTINUOUS OPERATION.

Application filed June 25, 1927, Serial No. 201,474, and in Germany June 12, 1924.

The invention relates to a process for refining heavy mineral oils by means of sulphur dioxide in a continuous operation. This is a continuation in part of an application filed September 13, 1924, Serial No. 5 737,542.

It is already known to refine light mineral oils by means of liquefied sulphur dioxide (SO_2). In this process the sulphur dioxide 10 is introduced from top to bottom and the oil to be refined from bottom to top, this counter-current resulting in the fact that the impurities saturated with SO_2 (the extract) settle below, whilst the purified oil, mixed 15 with SO_2 , deposes on the top.

If heavy mineral oils are to be refined, this process does not give a satisfying result. This resides in the fact that a mutual penetration of the two liquids does not take place 20 in the desired extent due to the nature of the heavy mineral oils; on the contrary, the liquefied SO_2 takes a few single ways only through the oil so that only a portion of the latter comes in contact therewith, whilst the 25 other oil particles remain unacted upon.

Consequently only individual quantities or charges could be treated with SO_2 by 30 intimately mixing the oil with the sulphur dioxide and causing the emulsion so formed to settle, after the churn or agitator had been thrown out of operation. The drawbacks the treatment of individual charges suffers from in comparison with a continuous operation are widely known and concern 35 substantially the economy of the operation. Since the possibility has been perceived of purifying mineral oils by a purely mechanical-physical method by treating them with sulphur dioxide, it has been tried to purify 40 also heavy mineral oils in a continuous operation like the light ones.

Now the possibility has been found of refining also heavy mineral oils by the aid of liquefied SO_2 in continuous operation, if the 45 mixing of the two liquids would be effected in a special vessel provided with an agitator and by continuously supplying the emulsion so formed in regulated quantities to a settling receptacle, where the emulsion enters, with constant reduction of its velocity, 50 within the so-called emulsion-zone, that is about in the midst. The entrance in the settling receptacle preferably takes place centrally, with an outward radial direction of

flow, this causing the emulsion to spread in the settling receptacle uniformly from the center and with the lowest possible flowing velocity. In this manner the occasion is offered to the emulsion to separate according to the specific weight of its constituents into extract and refined oil, these two constituents, firstly still mixed with SO_2 , then being drawn off on the top and bottom, respectively.

The specific nature of the process enables to accomplish the refining operation in several stages. This may be performed by effecting the mixing in a plurality of special vessels having agitators, and by continuously supplying the emulsions so formed to 60 separate settling receptacles where they enter, with constant reduction of their flowing velocity and enter the so-called emulsion-zone in a radial outward direction. The counter current principle is maintained therewith by the fact that the crude oil enters the last mixer, whilst the pure sulphur dioxide enters the first one, and that the refined oil leaves the first settling receptacle, whilst the extract leaves the last one. In 65 the intermediate stages the extract of the preceding stage is always mixed with the refined oil of the next stage.

In the accompanying drawings some embodiments of apparatus for carrying out the improved process are illustrated by way of 70 example. In these drawings:

Fig. 1 is a vertical section through an apparatus for carrying out the process in one stage,

Fig. 2 is a detail thereof in enlarged scale, 75 likewise in vertical section,

Fig. 3 is a somewhat modified arrangement of the apparatus of Fig. 1, in vertical section,

Fig. 4 is an apparatus according to Fig. 80 1 for carrying out the process in several stages,

Fig. 5 is an apparatus according to Fig. 85 3, likewise for carrying out the process in several stages.

As to be seen from Fig. 1, the unit consists of a mixer 7 fitted with an agitator 6. The sulphur dioxide enters at 8 and the heavy mineral oil at 9. The intimate mixture of oil and sulphur dioxide enters the 90 settling receptacle 11 in continuous operation through the pipe 10 and eventually 100

regulated by a throttling means. The pipe 10 preferably extends about to the midst of receptacle 11 and discharges the mixture in radial direction with the lowest possible speed by means of a distributor 12. Thereby a continuous separation of extract and refined oil takes place in a manner that uninterruptedly the refined oil can be drawn off at 13 and the extract at 14.

10 Fig. 2 shows in enlarged scale an embodiment of the distributor 12. As to be seen, the pipe 10 terminates in an annular slot 15 the cross section of which gradually enlarges so that the mixture can flow out horizontally in all directions with a relatively low speed.

15 In the embodiment shown in Fig. 3 the mixer 7 is connected through a pipe 10 to an inclined settling receptacle 27 in such a manner that the emulsion enters the so-called emulsion-zone with the lowest possible speed. This is obtained by a distributor 12 which is of a construction as described on the hand of Fig. 2. The inclined 20 position of the settling receptacle offers the advantage that the separation of refined oil and extract takes place more quickly than in a vertical receptacle. The refined product then leaves the settling receptacle at 13 again 25 and the extract at 14. By providing pipe holes 28 in the settling receptacles 11 or 27 the operation can be controlled at any time and regulated by adjusting the throttling members of pipe 10, so that the effect aimed 30 at is really obtained.

35 Fig. 4 shows by way of example three units 16, 17, 18, each of which corresponds to the apparatus of Fig. 1. The units are connected in series and so arranged that the 40 emulsion and the extract flow automatically, due to gravity, from the one into the other receptacle, whilst the refined oil is pumped over. The sulphur dioxide arrives through 45 19 in the mixer of the first unit 16 and the oil to be refined arrives through 20 in the mixer of the last unit 18. The fresh sulphur dioxide is mixed with the refined oil of the second unit 17, this oil being pumped over through pipe 21 by means of a pump 22 into 50 the mixer of the first unit 16 whilst the extract of the first unit flows through pipe 33 into the mixer of the second unit where it is brought together with the partly refined oil of the last mixer that is pumped over 55 through pipe 23 by a pump 24. The partly refined oil of the second unit enters through pipe 34 the mixer of the third unit where it comes in contact with the oil to be refined. Consequently refined oil flows out continuously from the settling receptacle of the first 60 unit 16 at 25, and extract flows out continu-

ously from the settling receptacle of the last unit 18 at 26.

Fig. 5 shows an apparatus consisting of three units 30, 31, 32 as shown in Fig. 3. 65 The flow of the liquids is here the same as in the apparatus shown in Fig. 4, except that the extract too must be pumped over by pumps 29. The pipes are denoted by the same reference numbers as in the embodiment of Fig. 4, and the direction of flow of the liquids is indicated by arrows.

70 What we claim as our invention and desire to secure by Letters-Patent, is:—

1. In a process for refining heavy mineral 75 oils by means of sulphur dioxide in continuous operation: preparing an intimate mixture of the oil and the sulphur dioxide in a vessel by means of a churning device, continuously supplying the mixture to a settling receptacle with a successively decreasing speed and at a zone located about in the midst of the mixture already contained in said receptacle.

80 2. In a process for refining heavy mineral 85 oils by means of sulphur dioxide in continuous operation: preparing an intimate mixture of the oil and the sulphur dioxide in a vessel by means of a churning device, continuously supplying the mixture to a settling receptacle with a successively decreasing speed at a zone located about in the midst of the mixture already contained in said receptacle, and causing the mixture to enter 90 said receptacle centrally and with a radial outward direction.

95 3. In a process for refining heavy mineral 100 oils by means of sulphur dioxide in continuous operation: preparing simultaneously a plurality of mixtures of the oil and the sulphur dioxide in a plurality of vessels by means of a plurality of churning devices, continuously supplying these mixtures each to a settling receptacle with a successively decreasing speed at a zone located about in 105 the midst of the mixture already contained in said receptacles, causing the mixture to enter said receptacles centrally and with a radial outward direction, the crude oil being supplied to the last and the pure sulphur dioxide being supplied to the first of said plurality of vessels, whilst the refined oil leaves the first and the extract the last of said plurality of settling receptacles, the vessels located between said first and last vessel being 110 supplied always with the extract of the preceding and with the refined oil of the next stage.
